UNITED STATES PATENT OFFICE.

MINNIE M. MELDRAM, OF NEW YORK, N. Y.

DESIGN FOR A DOLL.

55,569.

Specification for Design.

Patented June 29, 1920.

Application filed October 4, 1919. Serial No. 328,593. Term of patent 7 years.

To all whom it may concern:

Be it known that I, MINNIE M. MELDRAM, a citizen of the United States of America, residing at New York, in the county of New York and State of New York, have invented a new, original, and ornamental Design for a Doll, of which the following is a specification, reference being had to the accompanying drawing, forming part thereof.

In the drawing:

Fig. 2 is a side elevation thereof.

I claim:

The ornamental design for a doll, as shown.

MINNIE M. MELDRAM.
